(57) **CLAIM**

The ornamental design for a loon-shaped computer mouse, as shown and described.

DESCRIPTION

FIG. 1 is a front perspective view of a loon-shaped computer mouse, showing my new design;

FIG. 2 is a front view thereof;

FIG. 3 is a rear view thereof;

FIG. 4 is a right side view thereof with a left side view being a mirror image;

FIG. 5 is a top view thereof; and,

FIG. 6 is a bottom view thereof.

The broken lines shown in the drawings represent unclaimed portions of the loon-shaped computer mouse that form no part of the claimed design.
